UNITED STATES PATENT OFFICE.

JOHN M. KELLER, OF YOUNGSTOWN, OHIO.

INVALID-BED.

971,381.

Specification of Letters Patent. Patented Sept. 27, 1910.

Application filed November 11, 1908. Serial No. 482,146.

To all whom it may concern:

Be it known that I, JOHN M. KELLER, a citizen of the United States of America, and resident of Youngstown, county of Mahoning, and State of Ohio, have invented certain new and useful Improvements in Invalid-Beds, of which the following is a specification.

This invention relates to improvements in 10 adjustable invalid beds, and more particularly to a bed which is especially adapted for use in hospitals.

The primary object of the invention is to provide a bed composed of pivotally-connected 15 sections which may be readily adjusted without disturbance of or annoyance to a patient resting thereon, and having a removable seat portion, said bed being particularly designed for use in some cases of 20 appendicitis and septic peritonitis, wherein, after the usual surgical operation has been performed, it becomes necessary or desirable that the patient be held in what is known as the "Fowler position"—that is, in a 25 semi-reclining position with the knees elevated—for facilitating the natural drainage of pus from the peritoneal cavity and also the giving of the continuous saline injections so necessary in such cases for diluting 30 and carrying away the poisonous matter.

A further object of the invention is to provide a bed by means of which the hips and shoulders of the patient are held up without the aid of straps, and whereby the 35 body of the patient is caused to assume the "Fowler position" without inconvenience or discomfort.

A still further object is to provide a bed which may be readily adjusted for raising 40 and lowering a patient or invalid resting thereon to any position between a straight reclining position and an upright sitting posture. And a still further object is to provide a bed or chair which is particularly 45 adapted for use in cases of fractured legs, having a pair of separately-adjustable leg-sections adapted for use in independently adjusting the positions of the legs of a patient.

50 With these and other objects in view, the invention finally consists in the particular construction, arrangement and combination of parts which will hereinafter be fully described, reference being had to the accom-

panying drawings, forming a part of this 55 specification, in which—

Figure 1 is a side elevation of the invention; Fig. 2 is a view of the same partly in top plan and partly in broken section; Fig. 3 is a longitudinal section of the same on 60 the line 3—3, Fig. 2; Fig. 4 is a similar section, enlarged, on the line 4—4, Fig. 2; Fig. 5 is a horizontal section of the gear-casing on the line 5—5, Fig. 4, showing the gearing in top plan; and Fig. 6 is a perspective view of a supporting-latch.

Referring to said drawings, in which like reference-numerals designate like parts throughout the several views—1 indicates a rectangular metallic frame, formed preferably of angle-iron, adapted to be mounted upon a bed-frame 2 in any suitable manner. Mounted upon each side of said frame 1 at suitable points is a gear-casing 3, in which casings are journaled the ends of a pair of 70 transverse shafts 4 and 5, the latter having rigidly mounted thereon a pair of arms 6 which support the rectangular back-section 7, of a bed-frame which consists of said back-section 7, a rectangular seat-section 8, and a 75 pair of U-shaped leg-sections 9.

The adjacent ends of the back-section 7 and the seat-section 8 are pivotally connected, extensions 10 carried by the former being mounted upon adjustable pivot-pins 85 11 projected through longitudinal slots 43 in the sides of said seat-section. The opposite end of said seat-section has extensions 12 and 13 which are pivotally connected to the ends of the U-shaped sections 9. Each of 90 said sections 9 has at its opposite end a supporting-leg 14 having a laterally-directed pin 15 projected through a slot 16 in the frame 1 with an adjusting-nut 17 thereon whereby said leg may be held in any position to which it is adjusted along said slot 16. The supports for the said section 8 consist of a pair of arms 18 mounted upon a transverse shaft 19 which is journaled at its 95 opposite ends in gear-casings 20, similar to the casings 3, mounted upon said frame 1. Also journaled in said casings 20 is another transverse shaft 21. The purpose of these shafts will hereinafter be fully explained.

The section 7 of the sectional frame has a 100 mattress spring 22 of a wire-netting type stretched thereover for supporting a mattress section 23, and the sections 8 and 9

have stretched thereover a second mattress spring 24, the latter being divided to admit of independent movement of the two leg-sections 9. A second mattress section 25 is 5 mounted upon said second spring 24, as shown, said mattress being divided in a manner similar to that of the spring 24 for admitting of independent movement of said leg-sections.

10 Inclosed within each of the gear-casings 3 is a novel form of gearing, which consists of a bevel-gear 26 fixed upon the shaft 4, a spur-gear 27 fixed on the end of the shaft 5, and a shaft 28 having a bevel-gear 29 15 upon one end thereof in mesh with the bevel-gear 26, and a worm 30 about the body of the shaft 28 and in mesh with said spur-gear 27. The neck portions of said shaft 28 are journaled in bearings formed by transversely-directed webs 3^a and 3^b respectively carried by the casing sections 3^c and 3^d. The shaft 4 has a stem 31 projected outward from the casing 3 which is adapted for receiving thereon a crank or hand-wheel (not shown) 25 whereby said shaft may be rotated.

The gear-casings 20 inclose gearing which is precisely similar to that inclosed by the casings 3. As is obvious, when it is desired to elevate the back-section 7 to any position 30 between a straight reclining position and an upright position, the shaft 4 is rotated forward, and this action, through the gearing, causes the arms 6 carried by the shaft 5 to rise and force said back-section 7 upward 35 and forward, as shown in dotted lines in Fig. 1.

To adjust the seat-section 8 and leg-sections 9 to cause them to assume positions wherein the patient will be held in a partially reclining and partially sitting posture, with the knees elevated, as shown in dotted lines in Fig. 1, for forming a thigh-rest and a leg-rest, the shaft 21, which has a stem 51 similar to the stem 31, is rotated in a rearward direction, and this action, through the gearing inclosed by the casing 20, swings the arms 18 and the seat-section carried thereby upward and rearward. As the seat-section is raised, the leg-sections are inclined upward, the pins 15 carried by the legs 14 sliding rearward in the slots 16.

As is apparent, chance retraction of the parts is prevented by the use of the gearing herein shown and described.

55 Provided in the seat-section 8 is a small removable rectangular frame 38 which has mounted thereon a plate 39 and which is normally held in place by underlying latches 40 pivotally mounted on the frame 8. Said 60 plate 39 has fixed thereon a plurality of coil mattress-springs 41 on which is mounted an oval-shaped mattress section 42 which fills up a similarly-shaped opening in the mattress section 25 and in the mattress spring 65 24. Extensions 49 of the cloth covering of

the mattress section 42 are suitably fastened to the frame 38 so that the mattress section 42, springs 41, plate 39 and frame 38 may be together removed from the oval-shaped opening in the seat-section when the latter 70 occupies substantially the position illustrated in dotted lines in Fig. 1, for admitting of the use of a commode or bed-pan placed beneath said section, or for admitting of the use of a syringe or catheter. 75

When it is desired to adjust the seat-section to adapt the same for the use of a child or other patient whose legs are too short to permit of comfortable sitting with the legs flexed naturally at the knees, the 80 pivot-pins or bolts 11 are moved forward along the slots 43 to shorten the length of the seat, the rear end of the latter being thus permitted to project rearward behind the upraised back-section 7. Thumb-nuts 44 85 carried by said pins or bolts 11 are manipulated for holding the sections in adjusted positions.

Each supporting leg 14 has a longitudinal shank 45 with a longitudinal slot 46 therein, and said shank is adjustably connected to the side of the U-shaped section 9 by means of a bolt or pin 47 projected from the section 9 through said slot 46 and having a thumb-nut 48 thereon. By adjustment of 90 one or both bolts or pins 47 along the slots 46, one or both of the leg-sections of the bed may be elevated to a horizontal position when the seat-section occupies substantially the position shown in dotted lines in 100 Fig. 1, a feature which is particularly desirable in cases of fractured legs or other leg affections.

Anti-friction rollers 50 are provided on the ends of the arms 6, as shown. 105

From the foregoing it will be seen that I provide an extremely simple and convenient form of invalid or hospital bed which may be manipulated to raise or lower a patient occupying it to any desired position without 110 subjecting the patient to the disturbance or annoyance ordinarily attending movement from a reclining to a sitting posture, and vice versa.

Having thus described my invention, what 115 I claim as new, and desire to secure by Letters Patent, is—

1. A bed consisting of a plurality of pivotally connected frame-sections adapted for adjustment to elevate a patient resting 120 thereon to the "Fowler position" providing a body-rest, a thigh-rest and a leg-rest, adjusting means for said sections, and means whereby the thigh-rest may be adjusted with relation to the body-rest to vary the length 125 of the former when the "Fowler position" is assumed.

2. In a bed, a back-section frame, a seat-section frame and a leg-section frame, said frames being pivotally connected, rotatable 130

- means for adjusting the elevation of said back-section, separate rotatable means for adjusting said seat-section, said sections being adapted for adjustment to elevate a patient to the "Fowler position," and means whereby said seat section may be adjusted with relation to the back section to shorten the length of the seat section when the "Fowler position" is assumed.
3. In a bed, a back-section frame, a seat-section frame and a leg-section frame, said frame-sections being pivotally connected and said back-section frame and said seat-section frame being independently adjustable, supports for said frame sections, means whereby said supports may be adjusted for varying the positions of said sections, and means whereby the seat section may be adjusted with relation to the back section for shortening the length of the former when said sections occupy positions at substantially a right angle to each other.
4. In an invalid bed, a main frame and a sectional frame, bearings supported by said main frame, two independent pairs of shafts journaled in said bearings, said sectional frame consisting of a back-section, a seat-section and a leg-section, all pivotally connected, a pair of arms carried by one shaft of each pair, one pair of arms being directed rearwardly and in supporting engagement with said back-section and the other being directed forward and in supporting engagement with said seat-section, and gearing whereby said shafts may be rotated for varying the relative positions of said back and seat sections.
5. In an invalid bed, a main frame, bearings supported by said frame, two independent pairs of shafts journaled in said bearings, a sectional frame mounted over said shafts and consisting of a back-section, a seat-section and a leg-section, said sections being pivotally connected, a pair of arms carried by one shaft in supporting engagement with said back-section, a pair of arms carried by another shaft in supporting engagement with the seat-section, anti-friction rollers carried by each arm, independent means for rotating said shafts for varying the relative positions of said back and seat sections, and slidable supports for said leg-section.
6. In an invalid bed, a main frame, two sets of bearings supported by said frame, a pair of shafts journaled in each of said bearings, a sectional frame composed of a back-section, a seat-section and a leg-section, said sections being pivotally connected, arms carried by one shaft of each pair, the arms of one shaft being extended rearwardly and in supporting relation with said back-section
- and the arms of the other shaft being extended forward and in supporting relation with the seat-section, independent gearings 65 for each of said shafts, each gearing including a shaft bearing a bevel gear and a worm interposed between the shafts of a pair whereby motion communicated to one will be imparted to the other.
7. In an invalid bed, a main frame, bearings supported by said frame, a shaft journaled in each of said bearings, a sectional bed-frame composed of a back-section, a seat section and a pair of independent leg-sections, the back and seat sections being pivotally connected and both leg-sections being pivotally connected at one end to said seat-section, slidable supports for the opposite ends of said leg-sections, adjusting means 75 for each of said leg-sections, supporting arms for said back-section carried by one of said shafts, supporting arms for said seat-section carried by the other of said shafts, and independent gearings for said shafts. 80
8. In an invalid bed, a main frame, bearings supported by said frame, a shaft journaled in each of said bearings, a sectional bed frame composed of a back-section, a seat-section and a pair of independent leg-sections, the back and seat sections being pivotally connected and each of the leg-sections being pivotally connected at one end to said seat-section, slidable supports for the opposite ends of said leg-sections, supporting 90 arms for said back-section carried by one of said shafts, supporting arms for said seat-section carried by the other of said shafts, independent gearings for said shafts, a mattress spring carried by said back-section, 95 and a mattress spring carried by said seat and leg sections, the last-mentioned spring being divided to admit of independent movement of said leg-sections.
9. In a sectional bed, a seat-section having 100 a mattress spring stretched thereover and a mattress mounted thereon, said mattress and mattress spring having registering openings therethrough, and a removable section normally closing said opening, said removable section comprising a frame, latches pivotally mounted on said frame, a plate normally supported by said latches, springs mounted on said plate, a mattress section mounted upon said springs, and extensions 110 of the covering of said mattress section attached to said frame.
- In testimony whereof I affix my signature in presence of two subscribing witnesses.
